UNITED STATES PATENT OFFICE

2,179,592

ROLLER SKATE BRAKE

Theodore R. Geettie, Philadelphia, Pa.

Application February 24, 1939, Serial No. 258,282

4 Claims. (Cl. 280—11.20)

This invention relates to a brake for roller skates and it consists in the constructions, arrangements and combinations herein described and claimed.

5 It is an object of the invention to provide a structure in which braking action will be applied to the wheels of a skate through a bending action of the leg of a wearer of the skates, and in which the brake action is automatically released when 10 the leg assumes normal position.

It is also an object of the invention to provide a brake structure which may be readily installed upon skates now in use.

15 Additional objects, advantages and features of invention will be apparent from the following description considered in conjunction with the accompanying drawing, wherein

Figure 1 is a side elevation of a skate, partly in section, showing my brake applied.

20 Figure 2 is a bottom view thereof.

Figure 3 is a rear elevation of the skate.

Figure 4 is a sectional view of a portion of 15
skate having a modified form of brake installed.

Figure 5 is a perspective of the brake of the 20
modified form.

Figure 6 is a side elevation of a skate applied to 25
the foot of a user, indicating the mode of applying
the brake.

There is illustrated in Figures 1 and 2 a skate 30
10 having front and rear bracket members 11
and 12 to each of which there is mounted a truck
13 by means of a bolt 14. The bracket 11 is carried
by a forward section 15 extensibly connected
35 with a rear section 16 associated with bracket 12,
the sections being retained in adjusted position
by means of bolts 17. The construction described
is well understood in the art.

Upon each of the bolts 14 adjacent their inner 40
ends there is resiliently mounted a brake shoe
18, the shoes being apertured for reception of the
bolt, a helical spring 19 being interposed between
the shoe and truck 13. The shoes 18 comprise
45 oppositely disposed contact portions 20 for
braking action against respective rollers 21 of
the skate, and an upstanding medially disposed
apertured lug 22. The spring 19 functions to
maintain the brake in released position yet movable
50 to engage the wheels for braking action as will be described.

55 A lever 23 is swingably mounted upon the bolt
17 and includes a rearwardly extended operating
shank 24 apertured adjacent its free end to receive
a draw cable 25, the latter having means for
securement to the leg of the user, as clearly
shown in Figure 6. The cable 25 is preferably

passed through an eye 26 on the heel plate of
the skate, and as shown in Figure 2, the apertured
end of the shank 24 is approximately in
alinement with the eye so that upon application
of a drawing movement upon the cable, the shank 5
24 and lever 23 will be moved into the dotted line
position which would be that occupied during
application of the brakes.

A link 27 is pivotally connected to one end of the
lever 23, the other end of the link being fixed in 10
the aperture of the lug 22. A similar link 28 is
similarly connected to the lever 23 opposite the
bolt 17, and to the apertured lug 22 of the front
brake. Obviously, the brakes will be simultaneously
15 applied upon actuation of the lever 23, through
the cable 25, and when such pull is released,
the springs 19 will return the brakes to
inoperative position.

In Figure 4 the brake is shown applied only to
the rear truck of the skate. The mounting of 20
the brake shoe 18 is the same as that previously
described and the shoe comprises a shank 27 of
considerable length so as to extend rearwardly
through the medial portion of the truck, which is
then extended upwardly and at an angle, as indicated
25 in dotted lines. The upper end of the shank
terminates in a loop 28 for securement of
a strap or cable similar to the one 25. In this
form, bending of the knee of the user will cause
30 rocking of the brake shoe in a direction to impinge
upon the rollers of the skate.

While I have shown and described preferred
forms of my brake, this is by way of illustration
only and I consider as my own all such modifications
35 in structure as fairly fall within the scope of
the appended claims.

I claim:

1. In a roller skate having front and rear truck mounting brackets, a roller truck for each bracket, a bolt connecting respective brackets and trucks, a brake shoe loosely mounted upon the bolts, said shoe having oppositely disposed roller contact portions, a helical spring on each bolt interposed between a portion of the truck and the brake shoe normally holding the brake shoes in released position, a lever pivotally carried medially of the skate and movable in a plane parallel thereto, draw means connected between upper portions of the brake shoes and the lever, the connections with the lever being offset with respect to the pivot of the lever, said lever having an extension, strap means connected to the end of the extension, and said strap having means for attachment to the leg of a skater.
2. In a roller skate having front and rear truck 55

- mounting brackets, a roller truck for each bracket, a bolt connecting respective brackets and trucks, a brake shoe loosely mounted on the bolt of one of the trucks, said shoe having oppositely disposed roller contact portions, spring means cooperable with the brake shoe, for holding it in normal position, and draft means connected with the brake shoe and extended rearwardly of the skate and a pull strap connected to the free end of the draft means.
3. In a roller skate having front and rear truck mounting brackets, a roller truck for each bracket, a bolt connecting respective brackets and trucks, a brake shoe loosely mounted upon the bolts, said shoe having oppositely disposed roller contact portions, a helical spring on each bolt interposed between a portion of the truck and the brake shoe, normally holding the brake shoes in released position, a lever pivotally carried medially of the skate and movable in a plane parallel thereto, draw means connected between

the upper portions of the brake shoes and the lever, the connections with the lever being offset with respect to the pivot of the lever, said lever having a substantially right angular portion extended rearwardly of the skate, an eye on the skate above the right angular portion, and a draft cable threaded through the eye and connected to said rearward extension.

4. In a roller skate, a truck mounting, a roller truck for the mounting, a bolt connecting the truck and mounting, a brake shoe loosely mounted upon the bolt, said shoe having oppositely disposed roller contact portions, a helical spring on the bolt interposed between a portion of the truck and the brake shoe normally holding the brake shoe in released position, and said brake shoe having a medially connected lever of a length extended through the truck mounting and terminating in means for securingment of a pull strap.
